REVERSIBLE ENGINE CONTROL APPARATUS

Ralph T. Whitney, Irwin, Pa., assignor to The Westinghouse Air Brake Company, Wilmerding, Pa., a corporation of Pennsylvania

Application July 27, 1949, Serial No. 106,995

6 Claims. (Cl. 192—3.5)

1

This invention relates to control apparatus and more particularly to control apparatus for reversible engines.

In certain control apparatus for reversible engines a direction sensing device is employed which, in the usual form, comprises a friction shoe for actuation into friction contact with a rotating crank shaft of a reversible engine to sense the direction of rotation of same through resultant movement in a corresponding direction to condition certain valve mechanism accordingly.

In such a direction sensing device, the above mentioned friction shoe is moved into sliding frictional engagement with the rotating crank shaft by operation of fluid pressure piston means and held in such sliding engagement for considerable time at the expense of wear on the shoe.

It is a prime object of the present invention to provide an improved direction sensing device for sensing direction of rotation of such as a reversible engine crank shaft which comprises improved means for conditioning the valve mechanism therein.

Other objects and advantages will become apparent from the following more detailed description of the invention.

In the accompanying drawing; Fig. 1 is a schematic view substantially in section of a direction sensing device embodying the invention; and Figs. 2 and 3 are respective modifications of a portion of the device shown in Fig. 1.

Description

Referring to Fig. 1, the valve portion of the direction sensing device may comprise, in the usual form, a casing adapted to be mounted in a fixed position relative to a reversible engine and either on or immediately adjacent thereto. The casing usually encloses two poppet valves 1 and 2 contained in chambers 3 and 4 respectively, which chambers are open to such as forward and reverse control pipes 100 and 200, respectively. The poppet valves 1 and 2 are arranged side by side with parallel extending fluted stems 5 and 6, respectively, which stems extend into a chamber 7 common to both and connected to such as a pipe 300. The valves 1 and 2 control communication between the chamber 7 and the chambers 3, 4 respectively, hence between the pipe 300 and the forward and reverse control pipes 100 and 200, respectively. A spring 8 in each of the chambers 3 and 4 acts on the respective valve 1, 2 to urge same toward a closed position, in which position the valve 1 is shown in the drawing.

The valve stems 5 and 6 are adapted to be engaged by two spaced apart operating plungers 9 and 10, respectively, which are slidably mounted in the casing and provided with stems 11 and 12 which extend outwardly through said casing. Two rockable cams 14 and 15, fulcrumed on pins secured in the casing, are provided for actuating the stems 11 and 12, respectively, and thereby the valves 1 and 2, respectively. These cams may be identical, but reversely arranged, and each is operatively connected to the respective plunger 11, 12 through the medium of a follower element 17 which is rockably mounted on a pin secured in the casing. Each of the cams 14 and 15 is provided with a surface 19, which, when in engagement with the respective element 17, will unseat the respective valve 1 or 2. Adjacent to the surface 19, each cam is provided with a recess 20 which recess is adapted to receive the respective element 17 to permit movement of the respective plunger 9 or 10 by a spring 21 to a position disposed away from stems 5 or 6 to permit closure of the respective valve 1 or 2 by the respective spring 8.

The two cams 14 and 15 are operatively connected for movement in unison by a link 22, and since the cams are reversed as above mentioned, movement of the link and cams to the position in which they are shown in the drawing will effect opening of the valve 2 and closing of the valve 1, while movement of said link and cams in a clockwise direction, as viewed in the drawing, to a position in which the surface 19 on the cam 14 engages the respective element 17 will effect opening of the valve 1 and closing of the valve 2.

According to a feature of the invention, in lieu of the usual friction shoe for sliding frictional engagement with such as the outer surface of an engine crank shaft to actuate the valve mechanism, I provide a contact element 30 for rolling engagement with the engine crank shaft or with an element secured to rotate with the crank shaft.

In Fig. 1, the contact element 30 may be in the form of a segmental pinion 30 adapted for pivotal movement about a pin 31 secured to the casing between two opposite disengaged positions and during such movement into and out of engagement with teeth or serrations formed on the peripheral surface of a gear or similar element 32 which may be formed integral with or be removably attached to such as the engine crank shaft designated in the drawing by an appropriate legend. The contact element 30 is connected

to the pin 31 through the medium of an arm 33 which arm is operatively connected to the link 22 for actuating the valves 1 and 2 by a link 34, which link 34 is connected at its one end to said arm by a pin 35 (Fig. 2) and to said link 22 at its opposite end by a pin 36. The valves 1 and 2, cams 14 and 15, links 22 and 34, arm 33, and element 30 are held in the position in which they are shown in Fig. 1 by action of a tension toggle spring 37 which is pin connected at its opposite ends to the casing by a pin 38 and to the arm by a pin 39. Such position of the above elements is defined by contact of the element 30 with the projecting end of a piston rod 40 which is operatively attached to an actuating piston 41 shown in the drawing in a repose position, with said element 30 disposed away from the gear 32 at this time. In a position opposite to that in which it is shown in the drawing, the contact element 30 will be held by spring 37 in contact with a similar piston rod 42 attached to an actuating piston 43 which will then be in its repose position in which it is shown in the drawing, and the links 34 and 22 and cams 14 and 15 will be so positioned, as previously described, that the valve 1 will be open and the valve 2 closed with the chamber 1, hence pipe 300, closed to the chamber 4, hence pipe 200, and open to chamber 3, hence to the pipe 100. The spring 37 will act to hold the parts of the device in the above defined respective positions.

The pistons 41 and 43 are slidably disposed in respective oppositely arranged, coaxially aligned actuating cylinders 45 and 46 disposed on opposite sides of the contact arm 30. Each of the cylinders 45 and 46 may contain a light compression spring 50 disposed in an atmospheric chamber 51 at one side of the respective piston 41 or 43, which spring is arranged to urge said piston toward its repose position in which it is shown in the drawing in contact with a shoulder 52 formed in the casing. In each of the cylinders 45, 46 at the opposite side of the respective pistons 41 and 43 there is a pressure chamber 55, which in cylinder 45 is connected to a branch of the forward control pipe 100, and in cylinder device 46 is connected to a branch of the reverse control pipe 200.

In operation, with the engine crank shaft turning in its "Forward" direction, indicated by an arrow so titled in the drawing and with the contact element 30 disposed in the position in which it is shown in the drawing, with pipe 300 consequently connected to the reverse control pipe 200 by way of the unseated valve 2, assume that fluid under pressure is supplied to the forward control pipe 100 while the reverse control pipe 200 remains vented to atmosphere. Such fluid under pressure supplied to the forward control pipe 100 will flow to the pressure chamber 55 in the cylinder 45 and will cause, through movement of the piston 41 and attached rod 40, resultant movement of the contact element 30 into engagement with the teeth on gear 32 on the crank shaft rotating in its "Forward" direction. So long as the crank shaft continues to turn in its "Forward" direction, the contact element 30 will be held against further movement by rubbing contact with gear teeth 32. The effect of pressure of fluid in the chamber 55 acting on the piston 41 will be kept just sufficient to maintain such rubbing contact, as an excessive force of element 30 on gear teeth 32 is not desired from the standpoint of wear and may be kept at a minimum through proper design of the spring 50 for a given size piston 41 and for a given pressure of fluid. As soon as the engine crank shaft, hence the gear 32,

reverse direction of rotation, however, that is, from "Forward" to "Reverse" in compliance with the example, the teeth on gear 32 will mesh with the teeth of the contact element 30 to cause pivotal movement of the arm 33 about pin 31 to the opposite side of said gear, whereupon spring 37 will cause it to assume its opposite position in which the element 30 is disposed away from the teeth on gear 32 and in engagement with rod 42 attached to piston 43 in its repose position in which it is shown in the drawing, since chamber 55 in cylinder 46 is vented via the ahead control pipe 100 at this time. Such pivotal movement of the arm 33 will cause shifting of cams 14 and 15 and thereby resultant closing of the valve 2 and opening of the valve 1 for connecting the pipe 300 to the now vented ahead control pipe 100 for reasons beyond the scope of the present invention.

Similarly, while the crank shaft is yet rotating in its "Reverse" direction, if fluid under pressure is supplied to the reverse control pipe 200 while the forward control pipe 100 is vented, the piston 41 in cylinder 45 will be returned by spring 50 to its repose position, while fluid under pressure supplied to pipe 200 will flow to chamber 55 in cylinder device 46 and cause the piston 43 to move the contact element 30 into rubbing contact with the teeth on gear 32. As soon as the engine crank shaft reverses its direction of rotation, that is from "Reverse" to "Forward," the teeth on gear 32 will mesh with the teeth of element 30 to move arm 33 to the opposite side of said shaft whereupon spring 37 will snap it to its original position in which it is shown in the drawing, with said element 30 in contact with rod 40 attached to piston 41 in its repose position. As will be appreciated from previous description, the valves 1 and 2 will be positioned accordingly through resultant movement of links 34, 22 and cams 14 and 15.

In order to relieve shock and prevent undue wear of the two end teeth or serrations on element 30 which may result from rubbing engagement with the teeth on member 32 said end teeth 50 may be replaced by end teeth 70, referring to Fig. 2, which are pivotally connected to the element by means such as pins 71 and urged toward symmetrical relationship with the other teeth by such as leaf springs 72 in such a fashion that the teeth 70 will act a pawls which will ride the teeth on the crank shaft in one direction of its rotation and which will become effective to take hold when the crank shaft reverses its direction. The springs 72 may be secured by means of such as screws 73 to opposite sides of element 30 and arranged to urge the teeth 70 toward engagement with respective shoulders 74 formed in said element to accommodate the teeth. Rubbing engagement of the tooth 70 at either side of element 30 with teeth on the crank shaft will cause said tooth to leave shoulder 74 and pivot about pin 71 against action of the respective spring 72, thereby reducing the impact effect between element and shaft, while mating engagement of the tooth 70 with teeth on said shaft will allow return of said tooth into engagement with shoulder 74 to cause pivotal movement of arm 33 to the opposite side of said shaft in fashion as aforementioned herein.

In lieu of teeth or serrations either on the contact element 30 or on the crank shaft or a gear associated therewith, the contact element may be provided with a segmental shoe 80 of resilient material, such as rubber, as shown in Fig. 3. The

crank shaft need not be modified in any fashion to accommodate the shoe 80, but merely finished in the usual manner. When so urged by one or the other of cylinders 45 or 46, the shoe 80 will rub lightly against the crank shaft in rotation in one direction and will be wedged into rolling contact therewith when said shaft changes its direction of rotation, thereby causing shift of arm 33 to the opposite side of said shaft to condition valves 1 and 2 in fashion as aforescribed.

Summary

It will be seen that I have provided improved means for conditioning such as valve mechanism comprised in direction sensing devices according to the direction of rotation of a reversible engine.

Having now described the invention, what I claim as new and desire to secure by Letters Patent, is:

1. Apparatus for sensing direction of rotation of a reversible rotatable shaft comprising in combination, a pivotal element having a rest position at either side of and out of contact with said shaft and being adapted upon contact with said shaft to be moved thereby in the direction of either one or the other of said positions according to the direction of rotation of said shaft, a piston arranged to be operated by fluid under pressure to move said element from one of said positions into contact with said shaft, another piston arranged to be operated by fluid under pressure to move said element from the other of its positions into contact with said shaft, an engine forward control pipe arranged to convey fluid under pressure to and from said one piston, and an engine reverse control pipe for conveying fluid under pressure to and from said other piston.

2. Apparatus for sensing direction of rotation of a reversible rotatable shaft, comprising in combination, an annular element associated with said crank shaft for rotation therewith and comprising gear-like teeth around its peripheral face, a pivoted element comprising a segment having a series of gear-like teeth for intermeshing with the teeth of said annular element for moving said pivoted element from either side of said shaft in a direction toward a rest position at the opposite side and out of contact with said annular element, means for moving said pivoted element from either one of its rest positions into contact with said annular element, means carried by said pivoted element pivotally carrying opposite end teeth of said series, said pivoted element comprising means for supporting said end teeth for driving said pivoted element by said annular element only upon rotation of said annular element in a direction for moving said pivoted element from one side of said crank shaft toward the opposite side.

3. Direction sensing apparatus comprising in combination with a rotatable shaft, a contact element movable from either of two disengaged positions at opposite sides of said shaft into engagement with said shaft to be moved past said shaft by such engagement upon reversal in direction of shaft rotation, toggle spring means

operatively connected to said contact element to move said contact element to a respective one of said disengaged positions after passing said shaft, and fluid pressure means operatively connected to said contact element to overcome action of said toggle spring means to effect said engagement.

4. Direction sensing apparatus comprising in combination with a rotatable shaft, shaft gear teeth secured for rotation with said shaft, a contact element having rigidly attached corresponding gear teeth movable from either of two disengaged positions at opposite sides of said shaft into rubbing engagement with said shaft gear teeth when said shaft is rotating in one direction and movable past said shaft by meshing engagement with said shaft gear teeth upon reversal in direction of shaft rotation, toggle spring means operatively connected to said contact element to move same to a respective one of said disengaged positions after passing said shaft, and fluid pressure means operatively connected to said contact element to overcome action of said toggle spring means and effect said engagement.

5. Direction sensing apparatus comprising in combination with a rotatable shaft, an annular element having serrations about its periphery and arranged for rotation with said shaft, a pivotal element having serrations at one end for interlocking engagement with the serrations on said annular element for moving said pivotal element past said shaft, toggle spring means operatively connected to said pivotal element to move said pivotal element to a rest position free of said shaft after passing same, and fluid pressure means operatively connected to said pivotal element to move same against opposition of said toggle spring means for effecting such engagement.

6. Direction sensing apparatus comprising in combination with a rotatable shaft, a contact element having a resilient shoe movable from either of two disengaged positions at opposite sides of said shaft into endwise engagement with said shaft for rolling movement past said shaft upon reversal in direction of shaft rotation, toggle spring means operatively connected to said contact element to move same to a respective one of said disengaged positions after passing said shaft, and fluid pressure means operatively connected to said contact element to overcome action of said toggle spring means and effect said engagement.
